UNITED STATES PATENT OFFICE.

MARTINES CHICK, OF SAN DIEGO, CALIFORNIA, ASSIGNOR OF ONE-HALF TO
HARVEY McMURCHY, OF FULTON, NEW YORK.

TOOL FOR DECAPPING AND RECAPPING CARTRIDGE-SHELLS.

SPECIFICATION forming part of Letters Patent No. 739,151, dated September 15, 1903.

Application filed July 17, 1902. Serial No. 115,888. (No model.)

To all whom it may concern:

Be it known that I, MARTINES CHICK, of San Diego, in the county of San Diego, in the State of California, have invented new and useful 5 Improvements in Tools for Decapping and Recapping Cartridge-Shells, of which the following, taken in connection with the accompanying drawings, is a full, clear, and exact description.

10 This invention relates to an improved tool for decapping and recapping cartridge-shells.

The object is to produce a simple and practical device for removing caps from old or discharged shells and reinserting new or live 15 caps, so that the shell may be recharged by any one skilled in the art and reused as many times as may be practicable.

A more specific object is to construct the 20 device in such manner that two shells may be operated upon at the same time or separately, if desired—*i. e.*, one shell may be decapped and another one recapped by the same operation or the cap of a shell may be removed and a new one inserted by two successive 25 operations of the same device.

To this end the invention consists in the combination, construction, and arrangement of the parts of shell capping and decapping device, as hereinafter fully described, and 30 pointed out in the claims.

Referring to the drawings, Figure 1 is a 35 plan view of my invention, showing two shells in position, one to be decapped and the other to be recapped by one operation of the device. Figs. 2, 3, and 4 are respectively a plan, partly in section, a side elevation, also partly in section, and a rear end view of the device seen in Fig. 1, a shell being shown in Fig. 3 in position to be decapped and a portion of one of the levers being broken away 40 to show the plunger.

Similar reference characters indicate corresponding parts in all the views.

This tool may be made of any size or material, but is preferably of small size adapted 45 to be carried in the pocket to be used when desired, and the various parts are usually cut or stamped from sheet or bar metal and consists, essentially, of a head 1, a plunger 2, levers 3, and links 4. These various parts are assembled in a manner to be operated by hand, the head 1 being provided with abut-

ments 5 and 6 and recesses 7 and 8, the abutment 5 forming the rear face of the head to engage and hold the shell, as *a*, from endwise movement during the decapping operation, and the abutment 6 forms one of the walls of the recess 7 in the front face of the head to engage and hold the shell from endwise movement during the insertion of a cap, as *a'*, into the shell. These recesses 7 and 8 are disposed in planes at right angles to each other—*i. e.*, in the use of the tool. One recess, as 8, is regarded as vertical, being open at its upper end and closed at its lower end and made to 65 conform to the shape of the rim or head of the shell, while the recess 7 is horizontal and receives the inner or front ends of the levers 3 and also the front end of one part of the plunger 2. The head 1 is also provided with a vertical slot or capway 10 and a horizontal 70 guide or opening 11, the capway 10 being open at its upper side to receive the new caps and to hold them in position to be inserted or forced into the cap-seats in the heads of the 75 shells by the operation of the plunger 2. This capway 10 communicates with the recess 8, and the guide-opening 11 extends rearwardly from the way 10 to the rear face of the head or, rather, to the recess 7 and forms a convenient 80 guide for centering the plunger with the shell during the operation of inserting the cap in said shell.

The plunger 2 extends rearwardly from the central portion of the head 1, its front end 85 being guided in the opening 11 and its rear end carried by the links 4, a suitable spring 12 being employed to normally hold the forward end of the plunger back from the abutments 5 and 6 and also to hold the levers 3 90 and links 4 in their distended positions. This plunger is preferably constructed in two parts 2' and 2'', provided at their forward ends with dies 13 and 14, the part 2'' being pivoted at its rear end at 15 to the rear end of the part 95 2' to oscillate vertically and to receive the shell preparatory to decapping the same.

In this operation the shell is slipped over the free end of the part 2'', and the die 14 is aligned with and enters the opening in the 100 center of the cap-seat, whereupon the part 2'', with the shell thereon, is rocked toward the other part 2', so the rim of the shell is aligned with the abutment 5. The plunger is then

operated in a manner hereinafter described, which forces the rim of the shell against the abutment 5 and prevents the further movement of the shell; and the continued movement of the plunger causes its die 14 to force the cap from its seat, the spring 12 serving to return the plunger to its normal position. In a similar manner when it is desired to insert a new cap in the seat of the shell the rim or head of the shell is inserted into the recess 8. The cap is then inserted in the way 10, and the plunger is then operated, as before, to force the die 13 against the cap and to thereby press the cap firmly into its seat in the shell.

15 The front ends of the levers are pivoted at 16 to the head 1 at opposite sides of the plunger 2 and extend rearwardly beyond the rear end of said plunger, and the links 4 are pivoted at corresponding ends at 17 to the rear ends of the levers 3 and extend inwardly and forwardly and are pivoted at their inner ends at 18 to the rear end of the plunger, thus forming toggle connections between the levers and plunger. These levers and links 20 are normally held distended by the action of the spring upon the plunger 2 and are adapted to be compressed manually, the operator simply grasping the rear ends of the levers in one or both hands and forcing the same toward each other against the action of the spring 12, said spring returning the levers to their normal position through the medium of the plunger 2 and links 4.

25 In order to adapt my device to various sizes of cartridges, so that the caps will always be centered with the die or punch, I preferably make the plunger of such diameter as will receive the smaller cartridges easily and provide the same with centering means, consisting of springs 20, which are arranged lengthwise of the plunger and are secured in such manner as to expand outwardly automatically and at the same time are readily compressed by the cartridge and serve to hold said cartridge concentric with the axis of the die 14.

30 The operation of my invention having been fully described in the foregoing, it is apparent that one shell may be capped at the same time another is being decapped, or either operation may be effected singly.

35 Having thus described my invention, what I claim, and desire to secure by Letters Patent, is—

50 1. In a tool for decapping and recapping cartridge-shells, the combination with a head having at one side an abutment to hold the shell against longitudinal movement during the decapping operation, the opposite side of the said head also provided with an abutment to hold the shell against longitudinal movement during the recapping operation, of a plunger composed of two members, one being smaller than the other and mounted 55 thereon, the said smaller member carrying centering means thereon, and the larger mem-

ber carrying a punch at its forward end arranged to coact with the last-named abutment to force a cap into the shell, the said smaller member also carrying a punch at its forward end arranged to coact with the first-named abutment to remove a cap from the shell, and means for operating the said members simultaneously, substantially as described.

55 2. In a tool for decapping and recapping cartridge-shells, the combination with a head having at one side an abutment to hold the shell against longitudinal movement during the decapping operation, the opposite side of the said head also provided with an abutment to hold the shell against longitudinal movement during the recapping operation, the abutment connected by a guide-opening formed in the said head, and a capway formed in the said head for holding caps preparatory to the recapping operation, of a plunger composed of two members, one being smaller than the other and mounted thereon, the said smaller member carrying a plurality of springs arranged circumferentially thereof, 60 and a punch at its forward end, the larger member also carrying a punch at its forward end, the last-named punch adapted to operate in the said guide-opening, a spring surrounding the last-named punch and adapted to coact with the last-named abutment, and means for operating the said members simultaneously, substantially as described.

65 3. In a tool for decapping and recapping cartridge-shells, the combination with a head having at one side an abutment to hold the shell against longitudinal movement during the decapping operation, the opposite side of the said head also provided with an abutment to hold the shell against longitudinal movement during the recapping operation, the abutments connected by a guide-opening formed in the said head, and a capway formed in the said head for holding caps preparatory to the recapping operation, of a plunger composed of two members, one being smaller than the other and mounted thereon, the said smaller member carrying a plurality of springs arranged circumferentially thereof, 70 and a punch at its forward end, the larger member also carrying a punch at its forward end, the last-named punch adapted to operate in the said guide-opening, a spring surrounding the last-named punch and adapted to coact with the last-named abutment, and means for operating the said members simultaneously, substantially as described.

75 In witness whereof I have hereunto set my hand this 23d day of June, 1902.

MARTINEZ CHICK.
